Patented Dec. 23, 1924.

UNITED STATES PATENT OFFICE.

NIELS NIELSEN, OF PITTSBURG, CALIFORNIA.

AUTOMATIC STAMPING MACHINE WITH MAGAZINE.

Application filed September 11, 1923. Serial No. 662,185.

To all whom it may concern:

Be it known that I, NIELS NIELSEN, a citizen of the United States, residing in the city of Pittsburg, in the county of Contra Costa and State of California, have invented a new and useful Improvement in an Automatic Stamping Machine with Magazine, of which the following is a specification.

10 My invention relates to improvements in marking devices adapted for attachment upon can clinching machines and the like, for securing covers upon cans, whereby a characteristic mark may be made upon each can to identify the contents thereof during subsequent operations of a canning process.

The primary object of my invention is to provide an improved marking device for marking cans during a canning process.

20 Another object is to provide an improved device which is attachable directly upon a reciprocating part of a can clinching machine and operates in conjunction therewith for marking each can.

25 A further object is to provide an improved device which will accommodate a plurality of marking elements identifying different products.

Another object is to provide a device 30 which will facilitate the change of marking elements to correspond to a change in product.

A further object is to provide an improved device which will be continuous in 35 action and which may be adjusted to different products while the machine is in operation.

A still further object is to provide an improved device which is simple in construction and efficient in operation and which may be readily installed upon existing machines.

I accomplish these and other objects by means of the device disclosed in the drawings forming a part of the present specification wherein like characters of reference are used to designate similar parts throughout said specification and drawings and in which:

50 Fig. 1 is a side elevation of my improved marking device showing the manner in which the device is secured upon a can clinching machine,

Fig. 2 is a vertical section of the device,

Fig. 3 is a front elevation showing the 55 carrier in its uppermost position.

Fig. 4 is a similar view showing the carrier in full lines in its lowermost position and in dotted lines in the position to which it is moved when changing marking elements.

In the canning of vegetables and other products the goods to be canned, after suitable preparation, are placed in cans which are then fed through a machine, commonly 65 termed a can clinching machine, which operates to place and secure tops upon the filled cans. The cans are then passed through suitable cookers and subjected to the various steps of the canning process. The 70 labeling of the cans does not occur until after the cans have been passed through a number of distinct operations. As a number of different characters of goods as well as various grades of goods are commonly canned at 75 the same time it is necessary that each can be marked with a distinctive mark identifying the contents prior to labeling. Heretofore this has commonly been done manually, an employee being stationed near the 80 clinching machine to mark each can with its distinctive mark as it leaves the machine. As cans are fed through the machine at a rate of approximately forty per minute this marking is a laborious task requiring the 85 constant attention of the employee. My present invention is therefore designed to avoid this manual operation and to provide for the automatic marking of the cans as they leave the clinching machine. 90

Referring to the drawings the numeral 1 is used to designate in general the frame of a can clinching machine of the type used for clinching the tops upon square asparagus cans. As machines of this general character 95 are well known and form no part of the present invention no description is herein necessary other than to state that cans 2, previously filled with the product to be canned, are moved intermittently past a reciprocating member 3 upon which is carried one of a set of dies adapted to clinch the edges of a can and cover to secure the cover upon the can and seal the contents in the can. The cans 2 are fed in spaced relation 100 onto a conveyor not shown moving intermittently and timed to cause each can to be moved and held directly under the die while 105

the reciprocating member descends and clinches the top thereon, the next movement of the conveyor operating to move the sealed can from the machine and to move the succeeding can into position under the die.

My invention consists of a carrier 4 provided with a plurality of radially disposed arms 5 having gripping elements 6 secured upon the outer ends thereof. The carrier 10 is rotatably mounted upon an eccentric bearing 7 carried by a sleeve 8 secured upon a shaft 9. The shaft 9 is rotatably secured upon the top of the reciprocating member 3 by suitable blocks 11. A handle 12 is secured upon the outer end of the shaft 9 whereby the shaft and eccentric bearing 7 may be rotated to elevate the carrier 4 for a purpose hereinafter more fully described. The shaft 9 extends outwardly over the end 15 of the reciprocating member 3 and the carriage 4 is positioned upon the shaft so as to be directly above the point at which each can 2 stops after leaving the machine while the reciprocating member descends to clinch 20 the cover upon the succeeding can.

A marking element 13 is detachably secured upon the end of each arm 5 by means of the gripping elements 6, each marking element being provided with a resilient 25 stamp 14 made of rubber or other suitable material and having raised figures 16 formed thereon to print a designating mark upon the cans 2. The figures 16 may be of any suitable character adapted to designate different kinds and grades of goods, a different 30 figure or group of figures being used to designate each different kind or grade of product. It is preferable to provide a sufficient number of arms 5 to accommodate all the 35 marking elements necessary for a particular season's run upon the machine. The arms 5 are so spaced that only the lowermost marking element 13 will engage the cans 2 moved thereunder, the carriage being adjustably 40 secured in a desired position with the required marking element in operative position by means of a spring latch 17 engaging notches 20 formed around the edge of a ring 45 18 secured upon the hub 19 of the carrier.

The carrier is normally held in its operative 50 position with respect to the shaft 9 by a spring latch 21 arranged to engage a notch 22 formed upon a ring 23 secured upon the outer end of the sleeve 8 the eccentric bearing 7 being swung to its extreme lower position.

The operative marking element is inked 55 after each downward stroke by means of an inking pad 24 pivotally mounted upon a frame 26 secured upon a stationary portion of the frame 1 of the clinching machine adjacent the carrier 4. The pad is actuated by links 27 pivotally connected to the ends of the pad and to rods 28 having their upper 60 ends connected to the shaft 9 upon opposite

sides of the carrier 4. The rods 28 reciprocate vertically with the shaft and carrier and are guided by lugs 29 carried by the frame 26. Slots 31 are formed in side members 32 of the frame to permit a vertical 70 adjustment of the pad relative thereto whereby the pad may be caused to engage the printing surface of the adjacent marking element 13 as shown in Fig. 3 when the carrier 4 and the rods 28 are moved upwardly, by the upward stroke of the reciprocating member 3. During the downward movement of the carriage, the inking pad is swung outwardly from the path of the marking element by means of the links 27 75 and rods 28, in this manner permitting the marking element to be moved into contact with a can 2 as shown in Fig. 4. A spring 33 is secured upon the frame 26 and arranged to press against the back of one of the side 80 members 32 to normally hold the pad well up against the marking element to insure an effective inking and to afford a slight resilience against the pressure imparted by the links 27 when the carrier is moved downwardly. 85

In operation, my invention is as follows. The device being attached upon the clinching machine as above described, the carrier is set to place the desired marking element 90 in operative position. When now the machine is operated in its normal way the reciprocating member 3 of the machine will cause the entire carrier to be reciprocated in timed relation to the movement of cans 2 100 through the machine. Thus after the top is clinched upon each can by the reciprocating member 3 and its associated dies, the succeeding movement of the can will bring it directly under the marking element 105 so that the succeeding reciprocation will move the marking element against the can and cause a distinguishing mark to be imparted thereon. In this manner the cans are automatically marked for identification 110 throughout subsequent operations in the canning process.

When a change is made in the product being canned, the common practice is to place a block upon the conveyor by which the cans are moved. The block informs the operator of the clinching machine as to the nature of the new product and a short interval is allowed during which no cans are fed to the machine so that the operator may make any necessary adjustment to the machine. During this interval the operator adjusts the marking device to bring the desired marking element into operative position. In the construction shown in the drawings this is accomplished by turning the handle 12 until the eccentric bearing 7 is swung to its uppermost position relative to the shaft 9. The eccentricity of the bearing 7 is such that when the bearing is 120

swung to this position the entire carrier will be elevated sufficiently to cause the arms 5 and marking elements 13 to clear the inking pad 24 even when the reciprocating member has caused the carriage to be downwardly to the lowermost position of its stroke as shown in dotted lines in Fig. 4 of the drawings. While the carrier is in this raised position the operator selects the desired arm and marking element and rotates the carrier until this marking element is moved to the operative position, sufficient pressure being necessary to spring the latch 17 out of engagement with each notch until the desired retaining notch 20 is reached. As only an instant is required to turn the carrier to the desired position, the handle 12 may readily be held with one hand while the carrier is moved with the other. However, a notch 22 is provided upon the ring 23 and arranged to be engaged by the latch 21 when the bearing is turned to its extreme upper position in order that the carrier may be secured in inoperative position if desired.

From the above explanation it will be noted that the marking device may be adjusted and a different marking element placed in operative position without stopping the machine. This is an important feature of my invention as an interruption in the operation of the machine would cause a delay throughout the entire canning process.

While I have illustrated and described what I now consider to be the preferred form of my invention it is obvious that the form and arrangement of the several parts may be modified in many ways without departing from the spirit of my invention. I therefore do not wish to restrict myself to the details of construction disclosed but desire to avail myself of all modifications which may fall within the scope of the appended claims.

Having thus described my invention what I claim as new and desire to secure by Letters Patent is,

1. A can marking device comprising a carrier secured upon a reciprocating member of a can clinching machine arranged to clinch covers upon cans moved intermittently thereunder; a plurality of marking elements secured upon a carrier, one of which is normally held in operative position to engage and mark successive cans; and means for adjusting the carrier while the machine is in operation to hold a desired marking element in operative position.

2. A can marking device comprising a carrier secured upon a reciprocating member of a can clinching machine arranged to clinch covers upon cans moved intermittently thereunder; a plurality of marking elements secured upon the carrier, one of

which is normally held in operative position to engage and mark successive cans; and means for adjusting the carrier while the machine is in operation to hold a desired marking element in operative position; and means actuated by the reciprocating movement of the carrier for inking the operative marking element after each operation.

3. A can marking device comprising a rotatable carrier eccentrically mounted upon a reciprocating member of a can clinching machine arranged to clinch covers upon cans moved successively thereunder, a plurality of marking elements secured upon the carrier, one of which elements is normally held in operative position to engage and mark successive cans; and means for inking the operative element after each operation.

4. A can marking device comprising a rotatable carrier eccentrically mounted upon a reciprocating member of a can clinching machine arranged to clinch covers upon cans moved successively thereunder; a plurality of marking elements secured upon the carrier, one of which elements is normally held in operative position to engage and mark successive cans; and means for inking the operative element after each operation; and means for moving the carrier about its eccentric mounting to clear the inking means whereby the carrier may be rotated to bring another marking element into operative position while the machine is in operation.

5. A can marking device comprising a rotatable carrier eccentrically mounted upon a reciprocating member of a can clinching machine arranged to clinch covers upon cans moved successively thereunder; a plurality of marking elements detachably secured upon the carrier, one of which elements is normally held in operative position to engage and mark successive cans at the end of each downward stroke; and inking means mounted upon the machine and actuated by the movement of the reciprocating member and the carriage to engage and ink the operative marking element at the end of each upward stroke.

6. A can marking device comprising a rotatable carrier eccentrically mounted upon a reciprocating member of a can clinching machine arranged to clinch covers upon cans moved successively thereunder; a plurality of marking elements detachably secured upon the carrier, one of which elements is normally held in operative position to engage and mark successive cans at the end of each downward stroke; and inking means mounted upon the machine and actuated by the movement of the reciprocating member and the carriage to engage and ink the operative marking element at the end of each upward stroke; and means for moving the carriage upon its eccentric mounting to cause the marking elements to clear the ink-

ing means whereby the carriage may be rotated to place a desired marking element in operative position while the machine is in operation.

5 7. A can numbering device comprising a rotatable carrier mounted upon a reciprocating member of a can clinching machine arranged to clinch covers upon the tops of cans moved intermittently thereunder, said carrier being provided with a plurality of radially disposed arms; a marking element detachably secured upon the end of each arm one of which is normally held in operative position; an inking pad pivotally mounted upon the machine adjacent the carriage, said pad being arranged to engage and ink the marking surface of the operative element when in an up position; links reciprocating with the carriage and engaging the pad for moving the same out of the path of the marking element during the downward movement thereof, and to return said pad during the succeeding return stroke; and means for elevating the entire carriage relative to the inking pad to permit the marking elements

to clear the pad whereby the carriage may be rotated to place a desired marking element in operative position while the machine is in operation.

8. A can marking device comprising a shaft adapted to be secured upon a reciprocating member of a can clinching machine arranged to clinch tops upon cans intermittently thereunder, said shaft being provided with an eccentric bearing portion; a carrier 35 rotatably mounted upon said eccentric bearing portion said carrier being provided with a plurality of radially disposed arms; a marking element detachably secured upon the end of each arm, one of said markers being 40 normally held in operative position to engage and mark successive cans; and means for turning the shaft and eccentric bearing to lift the carriage out of operative position where by the carriage may be rotated to place 45 a desired marking element in operative position while the machine is in operation.

In witness whereof I hereunto set my signature.

NIELS NIELSEN.
